AIRLESS SPRAY GUN UTILIZING LOW PRESSURE COATING MATERIAL SOURCE

Joseph H. McNinch, Jr., and Robert J. Della Flora, Toledo, Ohio, assignors to The DeVilbiss Company, Toledo, Ohio, a corporation of Ohio

Filed Dec. 26, 1962, Ser. No. 246,979
12 Claims. (Cl. 239—124)

This invention relates to an airless spray gun which employs coating material from a relatively low pressure source and more particularly to a spray gun which, using low pressure coating material, raises the pressure of the material within the spray gun and ejects it as a finely atomized airless spray therefrom.

Spray guns capable of atomizing coating material without air are known in the art. Such spray guns provide good control over the coating material and substantially reduce overspray, which is inherent in the spraying operation when air is employed. With airless spray guns heretofore known, the coating material is placed under high pressure by a pump or other device located at a distance from the spray gun. Consequently, the pressure creating device, the hose and other portions of the system contain high pressure material and the systems are expensive because heavy, high quality hoses, pumps, tanks and other equipment are needed to create and contain the high pressure coating material.

The spray gun according to the present invention atomizes coating material by high pressure and without air and takes the coating material from a relatively low pressure source and increases the pressure only after the material has entered the spray gun. Consequently, only an ordinary low pressure source and hose equipment are required for the over-all coating system. The pressure of the coating material within the gun is raised by air or other suitable fluid under very moderate pressure supplied to the spray gun from a conventional air compressor. This is accomplished by means of a reciprocating piston assembly which enables the pressure of the coating material to be raised to a level higher than that of the fluid driving the piston assembly. The coating material is ejected by one portion of the piston assembly in rapid pulses which provide a substantially continuous flow of atomized coating particles.

It is, therefore, a principal object of the invention to provide an airless spray gun which requires only a low pressure on the coating material, and which eliminates the usual high pressure source and associated heavy hoses and other equipment.

Other objects and advantages of the invention will be apparent from the following detailed description of a preferred embodiment thereof, reference being made to the accompanying drawing, in which:

FIG. 1 is a schematic view in elevation of a spray gun and supplying equipment embodying the principles of the invention;

FIG. 2 is an enlarged view in vertical, longitudinal cross section of a portion of the spray gun shown in FIG. 1;

FIG. 3 is a view in cross section taken along the line 3—3 of FIG. 2.

Referring to the drawings, and more particularly to FIG. 1, a spray gun embodying the present invention is

2

indicated at 10 and includes a main body 12, a handle 14, and a trigger 16. The overall coating system also includes a main air line 18, a coating material line 20, and a relatively low pressure source 22 of coating material or paint. 5 The material in the container 22 is placed under pressure by air supplied through a line 24 from a storage tank 26 and a compressor 28.

Coating material from the source 22 is fed through the line 20 to an inlet passage 30 (FIG. 2) in the spray gun body 12. The inlet passage 30 communicates with a large annular chamber 31, which serves as a surge chamber, and an annular manifold 32. The latter is associated with a supply opening or ports 34 which are blocked by a check valve ring 36 which is urged to a closed position by a suitable spring 38. The opening 34, the ring 36, and the spring 38 constitutes check valve means by which coating material can enter a coating material chamber or cylinder extension 40 and a coating material cylinder 42 from the source 22, but cannot flow in the reverse direction.

The coating material is drawn into the chamber and cylinder when a coating material piston 44 is retracted or moved rearwardly to reduce the pressure in the chamber and cylinder under that of the coating material in the inlet 30. This pressure difference overcomes the force of the spring 38, moving the ring 36 away from the ports 34, so that the chamber 40 and the cylinder 42 are filled with coating material upon opening of the check valve ring 36. When the piston 44 moves forwardly again, the coating material in the chamber 40 and the cylinder 42 is placed under increasingly high pressure until the pressure becomes sufficient to overcome the force of a spring 46 and to move a pressure valve member 48 away from its seat 49 (as shown) within the group of outlet passages 50 communicating with the chamber 40. This occurs very quickly in the forward motion of the piston and the coating material flows through the outlet passages 50, a central outlet passage 52 in the member 48 and, hence, through a nozzle cap 54. The nozzle can be designed according to high pressure spray nozzles known in the art and does not constitute a novel part of the present invention.

The force of the spring 46 on the valve member 48 not only determines the pressure which the coating material in the chamber 40 and the cylinder 42 will reach before being ejected from the gun, but also determines a cut-off pressure below which no paint will issue from the gun. This prevents spattering or random flow of poorly atomized coating material particles. The spring 46 is located in a suitable retaining chamber 56 which is vented through a line 58 to the coating material supply so that leakage around the valve member 48 will not be a problem.

From the above, it will be apparent that the coating material is supplied through the outlet passage 52 in pulses, one during each cycle of the coating material piston 44, which pulses are so frequent as to establish an almost continuous spray when the trigger is pulled. It can be seen that the "off time" during which no paint is being discharged will determine the gaps in a spray pattern, and that this should be kept to a minimum. This requires a rapid return of the piston 44. The rate at which the coating material is sprayed can be regulated by a liquid control valve 60 which also can be unscrewed to

vent or bleed the chamber 40 before the initial painting operation. The valve 60 includes an adjustable needle 62 which can be adjusted with respect to a valve seat 64 to control an opening for a recirculation passage 66 communicating with the coating material chamber 40. The coating material which flows past the needle 62 is then recirculated through a return line 68 to the paint supply, again flowing through the annular supply manifold 32. By opening the valve 60, a greater quantity of the coating material can flow from the chamber 40, part of it flowing back through the passage 66 and the return line 68 to the supply manifold 32. This effectively increases the available discharge area through which paint can flow, which results in a greater speed of operation of the piston and an increase in the frequency of operation, as well as a reduction of the "on time" of the device. However, all of the coating material which does flow past the valve member 48 is at the same pressure, regardless of the degree to which the liquid control valve 60 is opened.

The coating material piston 44 is connected through a stem 70 to an intermediate or return piston 72 which is functionally integral with a power piston 74, the latter being provided with a suitable piston ring 76. The power piston 74 is located within a power cylinder 78 having an end wall 79 through which a portion of the intermediate piston 72 extends. The power piston 74 drives the coating material piston 44 forwardly when air or other suitable power fluid is applied to the rear of the power cylinder 78. The air supply for the power cylinder is provided through a controlled air supply passage 80 which is regulated by the trigger 16 and is connected to the air line 18. The passage 80 communicates with an air manifold 82 which has a plurality of passages 84 connecting the manifold 82 with a small annular valve chamber 86 adjacent a valve plate 88. The valve plate 88 has two positions, a rear one in which it contacts an exhaust valve seat 90, as shown, and a forward one in which it contacts a fluid power valve seat 92.

With the valve plate 88 in the rear position, the air in the small valve chamber 86 can flow between the valve plate 88 and the second valve seat 92 and, hence, into the rear of the cylinder 78. The piston 74 then moves forwardly in the cylinder 78 until the piston ring 76 moves beyond exhaust ports 94 located around the wall of the cylinder 78, which ports communicate with an exhaust manifold 96 and cylinder exhaust passages 98 and are effective to exhaust fluid from the cylinder 78 when the piston 74 has moved forwardly a predetermined distance. When the piston ring 76 moves beyond the ports 94, the air remaining in the end of the cylinder 78 is compressed and acts as a cushion for the piston 74, helping it to bounce back, thus aiding in bringing about the return stroke of the entire piston assembly. However, the major portion of the energy for the return stroke of the main power piston 74 is provided by air in an intermediate chamber 100 in which the intermediate piston 72 reciprocates, which air acts on the annular end of the piston 72 and urges it, along with the piston 74, rearwardly. The air for the chamber 100 is supplied through a passage 102 and a line 104 from a supply line 106 which communicates directly with the line 18. The supply line 106 is not controlled by the trigger 16 so that air pressure always exists in the chamber 100 and always urges the intermediate piston 72 and the entire piston assembly rearwardly, even when the trigger 16 is in the off position. Vent passages 107 are also formed in the gun body to accommodate the pumping action of the piston 44 and to vent any leakage of air or coating material from cylinders 42 and 100.

An air chamber 103 is located behind the valve plate 88 and is also supplied with line air from the supply line 106 through a suitable tube 110. The air pressure in the chamber 103 urges the valve plate 88 forwardly and moves it against the seat 92 after the cylinder 78 has been

vented when the edge of the piston 74 has moved forwardly to open the exhaust ports 94. The trigger-controlled air supplied through the passages 84 is then blocked from flowing between the valve seat 92 and the valve plate 88. As the valve plate 88 moves against the valve seat 92, it also moves away from the valve seat 90, so that air in the rear portion of the cylinder 78 can be exhausted through rear exhaust ports 112, passages 114, and exhaust outlets 115 as the piston 74 moves rearwardly. This release of air continues until the edge of the piston 74 moves over the rear set of exhaust ports 112 whereupon remaining air between the valve plate 88 and the power piston 74 is trapped. Further movement of the piston 74 builds up the pressure in the working cylinder 78 and causes the valve plate 88 to move again to its rear position against the valve seat 90.

As soon as the valve plate 88 has been forced to its rear position, power fluid from the line 84 again is supplied to the rear end of the cylinder 78 to again drive the piston 74 forwardly, the exhaust ports 112 now being blocked by the valve plate 88 and the valve seat 90. Once again, the piston 74 moves forwardly until the edge of the piston 74 moves beyond the forward exhaust ports 94, whereupon the drop in pressure in the cylinder 78 enables the air pressure in the air chamber 103 to move the valve plate 88 forwardly and thus block the flow of the supply air from the passages 84. The cylinder 78 then remains vented by means of the rear exhaust ports 112 communicating with the exhaust passages 114 and the exhaust outlets 115 until the piston 74 again reaches a rear position where the piston 74 covers or moves beyond the ports 112.

To review the overall operation of the spray gun 10, when spraying is to be initiated, air from the tank 26 is supplied to the source 22 to place the coating material therein under pressure. The material, under a pressure of 100 pounds per square inch, for example, is then fed through the line 20 to the inlet passage 30 and the surge chamber 31. At the same time, line air is supplied through the line 18 and the supply line 106 to the lines 102 and 104 and to the intermediate chamber 100. The air pressure in the chamber 100 then acts on the intermediate piston 72 and moves the main piston 74 to the rear position, if not already there. The air from the supply line 106 is also transmitted through the tubes 110 to the air chamber 103 which urges the plate 88 toward the front position against the valve seat 92.

Assuming that the paint cylinder 42 has been primed, the spray gun 10 is now in condition to spray coating material when the trigger 16 is pulled. When this is done, air is supplied through the passage 80, the manifold 82, and the passages 84 to the annular chamber 86 at the outer edge of the plate 88, this air also having a tendency to move the plate 88 to the rear position. A bleed hole 116 allows sufficient air to bleed into the power cylinder 78 to assure that the valve plate 88 will be forced to the rear position by allowing air from the passage 84 to enter the power cylinder. The bleed hole 116 is so small that it does not interfere with normal operation, and is usable or important only at a time of start-up. The air passes between the valve seat 92 and the plate 88 into the rear of the power cylinder 78. This air cannot escape through the exhaust ports 112 because the exhaust passage 114 communicating therewith is blocked by the seal effected through contact of the valve plate 88 with the valve seat 90. Hence, the air supplied to the rear of the cylinder 78 pushes the power piston 74 forwardly until the edge of the piston ring 76 uncovers the exhaust ports 94 whereupon the power air is vented through the exhaust passages 98. Valve 88 moves immediately to its forward position against seat 92 by means of the pressure in the chamber 103.

During the forward motion of the piston assembly the coating material piston 44 is driven forwardly in the cylinder 42 and forces coating material in the cylinder

42 and the chamber 40 to move through the passages 50, past the valve member 48, and out of the orifice in the cap 54, when the coating material reaches sufficient pressure to overcome the force of the spring 46. By way of example, the spring 46 is designed to prevent the valve member 48 from opening until the pressure of the coating material exceeds 900 pounds per square inch. Hence, the pressure of the coating material is raised from its inlet or supply pressure of approximately 100 pounds per square inch to at least 900 pounds per square inch when it is forced into the spray gun nozzle opening and out of the spray cap.

To regulate the quantity of coating material sprayed through the nozzle, while retaining it under the same pressure, the needle 62 is backed away from, or closed in towards, the valve seat 64 so that a greater or less quantity of the coating material in the chamber 40 and the cylinder 42 is recirculated through the passages 66 and 68 and into the supply manifold 32.

At this time, the exhaust ports 94 have exhausted air in the rear portion of the chamber 74 with the air pressure in the valve chamber 108 forcing the valve plate 88 forwardly. This has stopped the flow of the air from the manifold 82 and at the same time the exhaust ports 112 and the exhaust passages 114 to the rear exhaust ports 115 have been opened. Hence, air in the cylinder 78 is exhausted through the ports 112 during the rearward stroke of the piston 74. After the coating material piston 44 and the power piston 74 have reached the forward end of their strokes, they reverse and move toward the rear, due to the bounce force of the compressed air trapped in the front of the main cylinder 78 and the air bias on piston 72 in cylinder 100.

After the edge of the piston ring 76 moves rearwardly beyond the ports 112, the remaining air in the working cylinder 78 is trapped between the plate 88 and the piston 74, and as the pressure of the trapped air increases and its force exceeds the force of the air in the chamber 108 the plate 88 is forced to the rear position to open the air supply passages 84 which again reverses the direction of the piston 74. The piston 74 is then ready for another cycle.

During the reverse movement of the piston 74, the coating material piston 44 also is retracted in the cylinder 42, thereby admitting coating material through the check valve ports 34 and past the check valve ring 36 into the chamber 40 and the cylinder 42. Another cycle of the spraying operation also is then ready to commence. In practice, the pistons operate at a rate of 2000 to 6000 cycles per minute.

Various modifications of the above described embodiment of the invention will be apparent to those skilled in the art and it is to be understood that such modifications can be made without departing from the scope of the invention, if they are within the spirit and tenor of the accompanying claims.

What we claim is:

1. An airless spray gun comprising a spray gun body having therein a power cylinder and a coating material cylinder, a coating material piston in said coating material cylinder, a power piston in said power cylinder and having means connecting said power piston to said coating material piston, a valve plate at a rear portion of said power cylinder opposite the coating material cylinder, passage means in said spray gun body connected to the rear end of said power cylinder, means for supplying power fluid to said passage means, means forming a fluid control valve seat associated with said passage means and positioned to be engaged by said valve plate to prevent the flow of power fluid into said power cylinder from said passage means, means effective to urge said valve plate toward said valve seat, a rear exhaust port in said body located near the rear end of said power cylinder and effective to trap power fluid between said valve plate and said power piston when said

5 rear exhaust port is blocked as said power piston moves in a rearward direction, a rear exhaust passage communicating with said exhaust port, means forming an exhaust valve seat positioned to block said rear exhaust passage when contacted by said valve plate, additional 10 exhaust means effective to exhaust power fluid from said power cylinder when said power piston has moved forwardly in said cylinder a predetermined distance, means located outside said power cylinder cooperating with said connecting means between said power piston and said coating material piston to urge said power piston toward the rear of said power cylinder, coating material supply means communicating with said coating material cylinder, check valve means enabling the flow of coating material from said coating material supply means into said coating material cylinder and blocking the flow of coating material in the reverse direction, an outlet port in said body communicating with said coating material cylinder, nozzle means connected with said outlet port, a 15 pressure valve member blocking said outlet port, means urging said pressure valve member toward the blocking position, said urging means being yieldable to enable said pressure valve member to move to an open position when pressure of the coating material within said coating material cylinder rises above a predetermined amount, whereby coating material can flow to said nozzle means under high pressure.

2. An airless spray gun according to claim 1 wherein said additional exhaust means includes a forward exhaust port in said gun body located near the front end of said power cylinder and spaced from the front end a distance such that fluid is trapped between said power piston and said front end when said power piston passes said forward exhaust port when moving in a forward direction.

3. An airless spray gun according to claim 1 characterized by means for adjusting the coating material output of said spray gun.

4. An airless spray gun according to claim 3 wherein said output adjusting means includes recirculating passage means communicating with said coating material cylinder and said coating material supply means, and valve means in said recirculating passage means, said valve means being adjustable to control the amount of coating material which is recirculated from said coating material cylinder back to said coating material supply means.

5. An airless spray gun comprising a spray gun body having a coating material cylinder, a coating material piston reciprocable in said cylinder, power means connected to said piston for reciprocating the same, coating material supply means communicating with said coating material cylinder, check valve means enabling the flow of coating material from said supply means into said coating material cylinder and blocking the flow of coating material in the reverse direction, an outlet port in said body communicating with said coating material cylinder, nozzle means connected with said outlet port, a pressure valve member between said outlet port and said nozzle means and controlling flow of coating material to said nozzle means, means urging said pressure valve member to a closed position, said urging means being yieldable to enable said pressure valve member to move to an open position when pressure of the coating material in said coating material cylinder rises above a predetermined amount, whereby coating material can flow to said nozzle means under high pressure, and means in said spray gun body to change the coating material output of said spray gun without changing the length of the stroke of said coating material piston.

6. An airless spray gun comprising a spray gun body having a coating material cylinder, a coating material piston reciprocable in said cylinder, power means connected to said piston for reciprocating the same, a coating material supply passage communicating with said

coating material chamber, check valve means enabling the flow of coating material from said supply passage to said coating material cylinder and blocking the flow of coating material in the reverse direction, nozzle means spaced from said cylinder, outlet passage means connecting said cylinder and said nozzle means, pressure means preventing the flow of coating material from said cylinder to said nozzle means through said outlet passage means when the pressure of coating material in said cylinder is below a predetermined amount, said pressure means enabling the flow of coating material from said cylinder to said nozzle means when the pressure of the coating material exceeds the predetermined amount, recirculating passage means in said gun body connecting said cylinder with said supply passage, and regulating means in said recirculating passage to control the flow of coating material therethrough from said cylinder to said supply passage.

7. An airless spray gun comprising a spray gun body having a power cylinder, a power piston located in said power cylinder, coating material spray means including coating material pressurizing means located outside said power cylinder, means extending through an end wall of a front end of said power cylinder and connecting said power piston to a portion of said pressurizing means, a valve plate at a rear portion of said power cylinder opposite the end wall, passage means in said spray gun body connected to the rear portion of said power cylinder, means for supplying power fluid to said passage means, means forming a valve seat associated with said passage means and positioned to be engaged by said valve plate to prevent the flow of power fluid into said power cylinder from said passage means, means effective to urge said valve plate toward said valve seat independently of the position of said power piston, a rear exhaust port in said body located near the rear end of said power cylinder and effective to trap power fluid between said valve plate and said power piston when said rear exhaust port is blocked as said power piston moves in a rearward direction, a rear exhaust passage communicating with said exhaust port, means forming an additional valve seat positioned to close said rear exhaust passage when contacted by said valve plate, additional exhaust means effective to exhaust power fluid from said power cylinder when said power piston has moved forwardly in said cylinder a predetermined distance, means located outside said cylinder beyond said end wall and cooperating with said connecting means between said piston and said pressurizing means to urge said piston toward the rear end of said power cylinder, and trigger means for controlling the supply of power fluid to said passage means.

8. An airless spray gun comprising a spray gun body having a power cylinder, a power piston located in said power cylinder, coating material spray means including coating material pressurizing means located outside said power cylinder, means connecting said power piston to a portion of said pressurizing means, valve means at a rear end of said power cylinder opposite said pressurizing means, passage means in said spray gun body connected to the rear end of said power cylinder, means for supplying power fluid to said passage means, means forming a valve seat associated with said passage means and positioned to be engaged by said valve means to prevent flow of power fluid into said power cylinder from said passage means, means effective to urge said valve means toward said valve seat independently of the position of said power piston, a rear exhaust port in said body located near the rear end of said power cylinder, a rear exhaust passage communicating with said exhaust port, means forming an additional valve seat positioned to be engaged by said valve means and to close said rear exhaust passage, said valve means being forced against said additional valve seat by pressure trapped in said

power cylinder as said power piston moves rearwardly of said rear exhaust port, additional exhaust means effective to exhaust power fluid from said power cylinder when said power piston has moved forwardly in said cylinder a predetermined distance, and trigger means for controlling the supply of power fluid to said passage means.

9. An airless spray gun comprising a spray gun body having a power cylinder, a power piston located in said power cylinder, coating material spray means including coating material pressurizing means located outside said power cylinder, stem means extending through an end wall of a front end of said power cylinder and connecting said power piston to a portion of said pressurizing means, said stem means forming intermediate piston means, an intermediate chamber formed by said gun body beyond the end wall of said power cylinder and enclosing said intermediate piston means, passage means in said spray gun body connected to the rear end of said power cylinder, means for supplying power fluid to said passage means, valve means associated with said passage means for controlling the flow of power fluid from said passage means to said power cylinder, said valve means being opened when said piston is near the rear end of said cylinder, rear exhaust passage means in said body located near the rear end of said power cylinder, second valve means located in said exhaust passage means and being open when said power piston is moving in a rearward direction, a forward exhaust port in said gun body located near the front end of said cylinder and positioned to communicate with that portion of said power cylinder behind said power piston as said power piston nears the forward end of its stroke, and additional supply passage means communicating with said intermediate chamber for supplying power fluid thereto to act on said intermediate piston means and to urge said power piston toward the rear end of said power cylinder.

10. An airless spray gun comprising a spray gun body having a power cylinder, a power piston located in said power cylinder, coating material spray means including coating material pressurizing means located outside said power cylinder, stem means extending through an end wall of a front end of said power cylinder and connecting said power piston to a portion of said pressurizing means, passage means in said spray gun body connected to the rear end of said power cylinder, means for supplying power fluid to said passage means, valve means associated with said passage means for controlling the flow of power fluid from said passage means to said power cylinder, said valve means being opened when said piston is near the rear end of said cylinder, rear exhaust passage means in said body located near the rear end of said power cylinder, second valve means located in said exhaust passage means and being open when said power piston is moving in a rearward direction and additional exhaust means effective to exhaust power fluid from that portion of said power cylinder behind said power piston when said power piston has moved forwardly in said cylinder a predetermined distance.

11. An airless spray gun comprising a spray gun body having a power cylinder, a power piston located in said power cylinder, coating material spray means including coating material pressurizing means located outside said power cylinder, means connecting said power cylinder to said pressurizing means, passage means in said spray gun body connected to the rear end portion of said power cylinder, means for supplying power fluid to said passage means, fluid valve means associated with said passage means to regulate flow of power fluid to said power cylinder, rear exhaust port means in said body communicating with the rear end portion of said power cylinder, exhaust valve means for opening and closing said rear exhaust port, additional exhaust means for said power

cylinder and opened when said power piston travels forwardly a predetermined distance in said power cylinder to exhaust pressure from that portion of said power cylinder to the rear of said power piston, and means for controlling said fluid valve means to control the supply of power fluid to said power cylinder.

12. An airless spray gun according to claim 6 wherein said regulating means includes a control knob extending out of said gun body for manipulation by an operator. 10
